UNITED STATES PATENT OFFICE.

CHARLES G. HARGER, JR., OF CANTON, OHIO, ASSIGNOR TO GEORGE V. L. MELLINGER, OF SAME PLACE.

BED-CLOTHING CLAMP OR FASTENER.

SPECIFICATION forming part of Letters Patent No. 330,833, dated November 17, 1885.

Application filed January 10, 1885. Serial No. 152,466. (No model.)

To all whom it may concern:

Be it known that I, CHARLES G. HARGER, Jr., a citizen of the United States, residing at Canton, in the county of Stark and State of Ohio, having invented a new and useful article of manufacture, consisting of a Bed-Clothing Clamp or Fastener, of which the following is a specification.

My invention relates to a new article of manufacture, consisting of a bed-clothing clamp or fastener; and the objects of my invention are, first, to provide a light and attractive clamp or fastener, so constructed that when in use the bedding shall be held and retained in position by reason of the tension or pressure produced by the clamps. I attain these objects by the mechanism illustrated in the accompanying drawing.

The drawing is a perspective view of said invention.

It consists of a piece of steel wire or steel plate, or other desirable material bent upon formers, so as to produce a strut-spring, B, with a straight back, C, so constructed as to bring the pressure or tension of said clamp at the points E and D, respectively. When

in use, said clamp is passed over the wood-work edge of the bed in such a manner as to hold the bed-clothing in a fixed position between the points E and D. The flat back C 30 is placed upon the inside of the bed, and thus presents a smooth surface upon that side. The curved end of the outer limb of said clamp, as shown, A and E, can be used as a handle to remove said clamp from the bed.

It being evident that the clamp or fastener may be produced by other methods than that above described, I do not wish to be limited to any particular mode of manufacture of the same.

What I claim, and desire to secure by Letters Patent of the United States, is—

A bed-clothing clamp or fastener having a straight back, C, a central strut, B, and a forward portion terminating at its lower extremity in an outwardly-curved disengaging projection A, substantially as shown and described.

CHARLES G. HARGER, JR.
